UNITED STATES PATENT OFFICE.

JEPHTHA AVERY WILKINSON, OF BROOKLYN, NEW YORK.

RECEIVING AND PILING PAPER.

Specification of Letters Patent No. 25,068, dated August 9, 1859.

To all whom it may concern:

Be it known that I, JEPHTHA AVERY WILKINSON, of Brooklyn, in the county of Kings and State of New York, have invented, 5 made, and applied to use certain new and useful improvements in means for receiving and packing sheets of paper or other material as delivered from a printing-press or from a cutter that divides such material 10 into sheets; and I do hereby declare that the following is a full, clear, and exact description of the construction and operation of the same, reference being had to the annexed drawing, making part of this specification, 15 wherein—

Figure 1, is a vertical section of the said means or apparatus, and Fig. 2, is a plan of the same.

Similar marks of reference denote the 20 same parts.

My said invention consists in projecting the sheets through the air in such a manner that they fall in regular succession onto each other, and are taken away by an endless 25 apron or equivalent device to be stacked up in reams, or folded ready for use.

The drawing represents a device at *h*, for separating the sheets from an endless web, but the sheets may be delivered from 30 any suitable cutter or printing press.

o, is an inclined table onto which the sheet is delivered and passes between endless bands *p'*, and *p³*, formed in ranges of any desired number and passing around the 35 rollers and drums *p*, *p²*, 33, and 34. These rollers and drums are so located as seen in Fig. 1, relatively with the table *o*, that the bands *p³* travel on the surface of the able *o*, and then have an upward direction given 40 to them as they pass below the drum *p*, and up over the drum *p²* whence they return over the roller 34. The endless bands *p'*, pass direct from the drum *p*, around the roller 33. The effect of this part of the 45 packing apparatus is to receive the sheet between the bands *p'* and *p³* that gradually approach each other, and then impart to said sheet a slightly upward movement as it is projected rapidly from between the bands 50 and drums *p* and *p³* so that the sheets fall successively between the vertical sides *q²* in the manner represented by red lines Fig. 1, onto the table or apron *u*.

In order to prevent the sheets flying up-

ward by any current of air as projected I 55 make use of a series of belts *q*, intermediate to the belts *p'* on the drum *p*, said belts *q* passing around a roller or drum *r*, that is set in journal boxes on the vertical sides *q²*. This roller *r*, as well as the rollers *r'*, *r²*, *r³* 60 and *r⁴* are turned with alternating small and large parts or pulleys, so as to receive the endless bands *s*, in series as shown and said bands pass from the smaller part of one roller to the larger part of the next 65 whereby the speed of the bands is gradually lessened, and if any sheet travels against these bands its momentum will be checked until it finally subsides.

The vertical sides *q²* give direction to the 70 sheet and keep it in position widthways and also carry the rollers (*r*.) and bands (*s*.) forming thereby a trunk or receiver. The bands (*s*) are kept tight by the weight 35, with a cord over the pulley 36, to the shaft 75 of the roller *r⁴* that revolves in slotted journal boxes, and *q'* is a weighted roller to keep the bands *q* tight.

I prefer that the bands *p'* and *p³* travel faster than the sheet is delivered in order to 80 accelerate its speed and separate one sheet from the next, and to aid in so doing I employ narrow rollers *t*, *t*, of india rubber on a cross shaft acting against the outer and center bands *q*, *q*, *q*, as seen by dotted lines 85 in Fig. 2, to confine the paper to these bands in passing under the drum *p*.

By giving motion to the endless apron *u*, the sheets fall shingling, or one slightly behind the preceding, so that the handling is greatly 90 facilitated and said apron may be conveyed away any desired distance to accommodate folders or packers who may be located at tables on each side thereof. To give motion to this endless apron I use a wheel *u²*, driven 95 by a band from the shaft of the drum *p*, and pinions 37 give motion to the roller *u'*, around which said apron passes and *u³* is a roller at the other end of the table over which the apron passes, said roller being 100 fitted in adjustable bearings for tightening the apron.

What I claim as my invention and desire to secure by Letters Patent, is—

1. The accelerating bands *p'* *p³* and table 10 *o*, arranged and acting as set forth to project the sheets of paper successively over each other as they subside in the air, and in

combination with the foregoing parts I claim the endless apron receiving such sheets as specified.

2. I claim the retarding bands q and s , s , and trunk q^2 , in combination with the delivering bands p' , p^3 for the purposes and as specified.

In witness whereof I have hereunto set my signature this tenth day of June 1859.

JEPHTHA A. WILKINSON.
